UNITED STATES PATENT OFFICE.

CHARLES A. SCHNUR, OF ST. LOUIS COUNTY, MISSOURI, ASSIGNOR TO WAGNER ELECTRIC & MANUFACTURING COMPANY, OF ST. LOUIS, MISSOURI, A CORPORATION OF MISSOURI.

SHORT-CIRCUITING DEVICE FOR ELECTRIC MOTORS.

No. 922,521.

Specification of Letters Patent.

Patented May 25, 1909.

Application filed May 9, 1908. Serial No. 431,912.

To all whom it may concern:

Be it known that I, CHARLES A. SCHNUR, a citizen of the United States, residing in St. Louis county, in the State of Missouri, have 5 invented a certain new and useful Short-Circuiting Device for Electric Motors, of which the following is such a full, clear, and exact description as will enable any one skilled in the art to which it appertains to make and 10 use the same, reference being had to the accompanying drawings, forming part of this specification.

My invention relates to a short circuiting device for electric motors, and more particularly to that class of short circuiting devices 15 which consists of an annular member composed of laminæ of copper or other good conducting material, and adapted to be reciprocated laterally to connect the individual 20 members of a commutator or similar structure. In the present application I have shown an automatic device for securing the lateral reciprocation of the annular member, similar to that shown in the patent to J. H. 25 Blair, No. 742,280 of October 27, 1903. I do not wish, however, to limit myself to such a device, as the annular member may be reciprocated by any suitable device either automatic or manually operated. In short circuiting devices of this class which have heretofore been used, the individual laminæ of the annular member have been held together by means of a wire passed through holes formed in one end of each lamina. This wire 30 necessarily possesses considerable stiffness with the result that the annular member was difficult to place in position or remove from the device and that the bending of the wire often caused part of the laminæ to be held 35 out of contact with the commutator bars, thus interfering with the proper operation of the device.

The object of the present invention is to provide means for retaining the laminæ in 40 position which will overcome the above objections.

In the accompanying drawings which illustrate one form of short circuiting device made in accordance with my invention, Figure 1 is a longitudinal central section; Fig. 2 is an end view of a portion of the short circuiting ring; Fig. 3 is a view of one of the short circuiting laminæ the end retaining band or ribbon being shown, and Fig. 4 is a

view similar to Fig. 3 but showing the retaining band or ribbon in section. 55

Like marks of reference refer to similar parts in the several views of the drawings.

5 represents the armature shaft. Secured to the shaft 5 is a cup-shaped casing 6 upon the rim of which the commutator is fastened. This commutator consists of bars or segments 7 separated by the usual insulation 8. The commutator bars or segments 7 are insulated from the casing 6 by means of an insulating ring 9 and are secured in position by means of a beveled ring 10 and set screws 11.

12 is a continuous contacting ring set into the inner face of the cup-shaped casing 6 and adapted to be electrically connected with the bars or segments 7, as will be hereinafter more fully described.

15 is an annular member surrounding the shaft 5. The inner face of the member 15 is beveled, as shown at 16 Fig. 1, and the cup-shaped casing 6 is provided with an oppositely inclined face 17. Between these two inclined faces are arranged wedge-shaped weights 18 which are adapted to be moved outwardly by centrifugal force so as to reciprocate the annular member 15. The member 15 is normally held in the position shown in Fig. 1 by means of a coil spring 19, bearing at one end against the annular member 15 and at the other against a collar 20 on the shaft 5. Formed in the periphery of the annular member 15 is a groove 22 in which is placed the annular short circuiting ring now 90 to be described.

The short circuiting ring which is placed in the groove 22 consists of a large number of laminæ 23 of copper or other good contacting material. Each of the laminæ 23 is provided with a pair of projecting contacts 24, one of which is adapted to bear against one of the segments 7 of the commutator and the other upon the contacting ring 12 when the short circuiting ring is moved into operative position. In each of the laminæ 23 is formed a slot 25 adapted to receive a band or ribbon 26 of flexible metal such as copper, brass or the like. The slots 25 are of slightly greater width than the thickness of the band 26 but are preferably or substantially the same length as the width of said band. The material of the laminæ 23 may be cut away 105 at the interior of the band 26 as shown at 27,

Fig. 4. The band 26 is made of slightly greater length than the combined thickness of the various laminæ 23 so as to project somewhat at the ends, as shown at 29, Fig. 2. 5 The ends of the band 26 are slit and bent over portions 30 are thus formed which serve as retaining means for the laminæ of the short circuiting ring.

In order to assemble the parts it is merely necessary to withdraw the annular member 10 15 from the cup-shaped casing 6 and apply the ring to the groove 22, no additional retaining means being required. Owing to the great flexibility of the band 26, and to the 15 play allowed between the band and the laminæ 23 the laminæ at all times make perfect contact with the contacting ring 12 and with the various segments 7 of the commutator.

Having fully described my invention, what 20 I claim as new and desire to secure by Letters Patent of the United States, is:

1. In a short circuiting device for electric motors, the combination with a plurality of insulated contacts, of a reciprocating member, short circuiting laminæ carried by said member for electrically connecting said contacts, and a flexible metallic ribbon connecting said laminæ.

2. In a short circuiting device for electric 30 motors, the combination with a plurality of insulated contacts, of a reciprocating member, short circuiting laminæ carried by said member for electrically connecting said contacts, each of said laminæ being provided 35 with a longitudinal slot and a flexible metallic ribbon extending through said slots.

3. In a short circuiting device for electric 40 motors, the combination with a plurality of insulated contacts, of a reciprocating member, short circuiting laminæ carried by said member for electrically connecting said contacts, each of said laminæ being provided with a longitudinal slot and a flexible ribbon 45 extending through said slots, said ribbon be-

ing of less thickness than the width of said slots.

4. In a short circuiting device for electric 50 motors, the combination with a plurality of insulated contacts, of a reciprocating member, short circuiting laminæ carried by said member for electrically connecting said contacts, and a flexible metallic ribbon connecting said laminæ, said ribbon being provided with retaining means for said laminæ.

5. In a short circuiting device for electric 55 motors, the combination with a plurality of insulated contacts, of a reciprocating member, short circuiting laminæ carried by said member for electrically connecting said contacts, and a flexible metallic ribbon connecting said laminæ, said ribbon having bent ends forming retaining means for said laminæ.

6. In a short circuiting device for electric 60 motors, the combination with a plurality of insulated contacts of a reciprocating member, short circuiting laminæ carried by said member for electrically connecting said contacts, and a flexible metallic ribbon connecting said laminæ the length of said ribbon being greater than the combined thickness of 70 said laminæ.

7. In a short circuiting device for electric 75 motors, the combination with a plurality of insulated contacts, of a reciprocating member, short circuiting laminæ carried by said member for electrically connecting said contacts, and a flexible connector engaging with but having movement relative to all of said laminæ, whereby said laminæ have uniform 80 freedom of movement.

In testimony whereof I have hereunto set my hand and affixed my seal in the presence of the two subscribing witnesses.
